US00D755833S

(12) **United States Design Patent**
Lim et al.

(10) **Patent No.:** **US D755,833 S**
(45) **Date of Patent:** **** May 10, 2016**

(54) **DISPLAY SCREEN OR PORTION THEREOF
WITH ICON**

(71) Applicant: **Samsung Electronics Co., Ltd.,**
Suwon-si (KR)

(72) Inventors: **Eun-Sil Lim, Seoul (KR); Jee-Yeon
Wang, Seoul (KR); Ho Kim, Seoul (KR)**

(73) Assignee: **Samsung Electronics Co., Ltd.,**
Suwon-si (KR)

(**) Term: **14 Years**

(21) Appl. No.: **29/458,129**

(22) Filed: **Jun. 17, 2013**

(30) **Foreign Application Priority Data**

Feb. 23, 2013 (KR) 30-2013-0009505
(51) **LOC (10) Cl.** **14-04**
(52) **U.S. Cl.**
USPC **D14/489**
(58) **Field of Classification Search**
USPC D14/485-495
CPC G06F 3/04817; G06F 3/0482
See application file for complete search history.

(57) **CLAIM**

The ornamental design for a display screen or portion thereof with icon, as shown and described.

DESCRIPTION

FIG. 1 is a front view of a display screen or portion thereof with icon, showing our new design; and,
FIG. 2 is a front view of a second embodiment thereof.
The broken lines represent a boundary of the claim and form no part of the claimed design.

1 Claim, 2 Drawing Sheets
